(57) **CLAIM**

The ornamental design for an edge ring, as shown and described.

DESCRIPTION

FIG. 1 is a front isometric top view of an edge ring.

FIG. 2 is a top plan view thereof.

FIG. 3 is a bottom plan view thereof.

FIG. 4 is a first side view thereof.

FIG. 5 is a second side view thereof.

FIG. 6 is an enlarged partial view of the section 6 shown in FIG. 1.

FIG. 7 is a cross sectional view along line 7-7 of FIG. 2 thereof.

FIG. 8 is an enlarged partial side view thereof.

FIG. 9 is an enlarged partial view of the section 9 shown in FIG. 2.

FIG. 10 is an enlarged partial cross sectional view of the section 10 shown in FIG. 7.

FIG. 11 is another front isometric top view thereof assembled with an overhang ring.

FIG. 12 is another top plan view thereof assembled with the overhang ring.

FIG. 13 is a third side view thereof assembled with the overhang ring; and,

FIG. 14 is an enlarged partial cross sectional view along line 14-14 of FIG. 12 thereof assembled with an overhang ring. The broken lines appearing in FIGS. 1-14 illustrate portions of the edge ring assembly that form no part of the claimed

(Continued)

design. The dot-dot-dash broken lines show boundaries of cross sectional or enlarged views that form no part of the claimed design.
